UNITED STATES PATENT OFFICE.

NELSON DOUGLAS WELLS, OF TULSA, INDIAN TERRITORY.

WELL-DRILLING MACHINE.

No. 871,014.

Specification of Letters Patent.

Patented Nov. 12, 1907.

Application filed April 21, 1906. Serial No. 312,983.

To all whom it may concern:

Be it known that I, NELSON DOUGLAS WELLS, a citizen of the United States, and a resident of Tulsa, District No. 8, Indian Territory, have invented a new and Improved Well-Drilling Machine, of which the following is a full, clear, and exact description.

The object of the invention is to provide a new and improved well-drilling machine arranged to permit convenient actuating of the drill-rod at the beginning 10 of the drilling operation by the employment of a spudding device, without the use of the walking-beam, and to allow convenient and quick lifting of debris, &c., out of the well, independent of the spudding device and walking-beam.

15 The invention consists of novel features and parts and combinations of the same, as will be more fully described hereinafter and then pointed out in the claims.

A practical embodiment of the invention is represented in the accompanying drawings forming a part of 20 this specification, in which similar characters of reference indicate corresponding parts in all the views.

Figure 1 is a side elevation of the improvement; Fig. 2 is a cross section of the same, on the line 2—2 of 25 Fig. 1; Fig. 3 is a plan view of the improvement; Fig. 4 is an enlarged side elevation of the friction-drive for winding up the lifting or sand rope, the section being on the line 4—4 of Fig. 3; Fig. 5 is a side elevation of a modified form of the spudding device; Fig. 6 is an enlarged perspective view of a modified form of the support for the crank-shaft; and Fig. 7 is an enlarged side elevation of another modified form of the same.

On a suitably constructed frame A is adjustably mounted the frame B' of an engine B or similar motor, 35 having its main shaft B² provided with a pulley C connected by a belt C' with a pulley C² secured on a crank-shaft D journaled in suitable bearings carried on the main frame A. The crank-shaft D is connected at its crank-arm D' by the usual pitman E with a walking-beam F, for operating the drill in the usual manner.

In order to insure a proper connection of the belt C' with the pulleys C and C² it is desirable to adjust the frame B' of the engine lengthwise on the frame A, to hold the belt C' taut, and for this purpose a screw G is 45 preferably employed, abutting with its head against an abutment G' secured to and forming part of the main frame A, the screw also screwing in a nut G² held on the cross-beam B³ of the engine-frame B'. Thus, when the screw-rod G is turned, the frame B' of the engine can be adjusted lengthwise on the main frame A, so as to bring the belt C' in taut position, for the proper transmission of the power from the engine to the crank-shaft D. When the desired adjustment of the engine-frame B' has been made, then the engine-frame 50 is securely locked in position on the main frame A by suitable bolts B⁴, as plainly shown in Figs. 1 and 2.

At the beginning of the drilling operation the walking-beam F is not used, and instead a drill-rope H is employed, extending over a pulley on the derrick, to connect at one end with the drill and to wind up at its 60 other end on a spool or reel I, secured on a shaft I' mounted to turn in suitable bearings attached to the main frame A. This drill-rope H is actuated by a spudding device J driven from the crank-shaft D and arranged in such a manner as to impart the desired 65 movement to the drill-rope H, for the latter to alternately raise and lower the drill-rod, for drilling the well. When the well has been drilled for say about one hundred feet, then the drill-rope H is disconnected from the spudding device and connected with the 70 walking-beam F for drilling the well deeper, in the usual manner.

The spudding device J is arranged as follows: A pulley J' engages the drill-rope H and is journaled on the free end of a rock-arm J², fulcrumed at its lower 75 end at J³ on the main frame A. The rock-arm J² is pivotally connected with the eccentric-rod J⁴ of an eccentric J⁵ secured on the crank-shaft D, so that when the latter is rotated the eccentric J⁵ and its eccentric-rod J⁴ impart a rocking motion to the rock-arm J², 80 whereby the pulley J' alternately pulls and releases the drill-rope H, held stationary at the spool or reel I, and the drilling tools are alternately lifted and dropped, for drilling the well.

As the well is drilled it is necessary to feed out 85 more drill-rope H, and for this purpose the spool or reel I is periodically turned, to unwind more drill-rope H, and after the desired amount of drill-rope H has been unwound, the shaft I' of the spool I is held against turning, and for this purpose a suitable brake 90 mechanism is employed, preferably consisting of a brake-wheel K secured on the shaft I' and engaged by a brake-band K', fixed at one end and connected at its other end with a lever K² having a handle K³, under the control of the operator, for applying and releasing 95 the brake-band K'.

The spool or reel I is adapted to be periodically driven from the crank-shaft D at the time the brake mechanism is off, and for this purpose the shaft I' is provided with a pulley L, connected by a belt L' with 100 a pulley L², mounted loosely on the crank-shaft D and adapted to be connected with the same by a clutch L³, thrown in and out of gear by a lever L⁴ connected by a link L⁵ with the brake-lever K², so that when the operator throws the brake-handle K³ downward the 105 brake-band K' is applied on the wheel K, and at the same time the clutch L³ is thrown out of gear, to disconnect the crank-shaft D from the pulley L². When it is desired to turn the spool or reel I for unwinding some of the drill-rope H, then the operator swings the 110 handle K³ upward and in doing so releases the brake mechanism and at the same time causes the clutch L³

to connect the crank-shaft D with the pulley L². When this takes place the rotary motion of the crank-shaft D is transmitted by the clutch L³, pulley L², belt L' and pulley L to the shaft I' of the spool or reel 5 I, to unwind a portion of the drill-rope H. When this has been done, then the handle K³ is returned to its normal position, to throw the clutch L³ out of gear and thereby stop the rotation of the spool I, at the same time locking the latter against turning movement 10 by the application of the brake mechanism. To wind up the drill the clutch is thrown into operative position and the motor reversed.

The hoisting or sand rope N for hoisting debris or other matter out of the well winds on a spool or reel O, 15 having its shaft O' journaled in bearings O² and O³, of which the bearing O² is fixed on the main frame A and the other bearing O³ is in the form of a pivoted arm, mounted to swing on the main frame A. A rod O⁴ is pivotally connected with the bearing O³, to 20 allow of imparting a swinging motion to the bearing O³. On the shaft O' is secured a friction-pulley O⁵, adapted to be thrown in engagement either with a friction-pulley O⁶ secured on the crank-shaft D or with an abutment O⁷ secured to the main frame A. When 25 the operator pulls on the rod O⁴, the pulley O⁵ is moved in frictional contact with the pulley O⁶, to drive the shaft O' and the spool O from the shaft D, to wind up the rope N, and when the rod O⁴ is pushed from the right to the left, then the pulley O⁵ is moved in engagement with the abutment O⁷, to bring the shaft O' 30 and the reel O quickly to a standstill. Thus, by the operator manipulating the rod O⁴, the spool or reel O can be quickly actuated, with a view to wind up the lifting-rope N or to stop the rotation of the spool 35 after the lifting operation has been completed.

The modified form of spudding device shown in Fig. 5 consists essentially of an eccentric P, secured on the crank-shaft D, and the eccentric-strap P' of this eccentric is mounted on ball-bearings P² and the strap is in 40 the form of a pulley, for the passage of a rope P³ having loops P⁴ and P⁵ at its ends, of which the loop P⁴ is hung onto the spool I while the loop P⁵ engages the drill-rope H. When the shaft D is rotated the eccentric P imparts the desired motion to the rope P³, 45 to actuate the drill-rope H, for raising and lowering the drilling tools. If desired, the loop P⁴ may also be engaged with the drill-rope H, when it is desired to give less stroke to the drill-rope H.

The bearings for the crank-shaft D may be of any approved construction, such, for instance, as indicated 50 in Fig. 1, Fig. 6 or Fig. 7, but it is evident that I do not limit myself to any one of the particular constructions shown, as the same can be varied without deviating from my invention.

Having thus described my invention, I claim as new 55 and desire to secure by Letters Patent:

1. A well-drilling machine comprising a walking beam, a drill-rope, a spool for the same, a crank-shaft for connection with the walking-beam, a spudding device actuated from the said crank-shaft and connected with the said 60 drill-rope, a brake mechanism connected with the said spool, to hold the latter against turning, and a driving device for unwinding the drill rope from the said spool, connected with the said crank-shaft, the said driving device having a clutch operating in conjunction with the said 65 brake mechanism.

2. A well drilling machine, comprising a walking beam, a crank shaft for connection with the walking beam, a friction wheel on the crank shaft, a spool for a hoist rope, a friction disk on the spool, said spool being movable toward 70 and from the crank shaft whereby to move the friction disk into and out of contact with the friction wheel, a spool for a drill rope, a connection between said spool and the crank shaft for operating said spool, a brake mechanism on the spool shaft, and a link connection between the 75 brake mechanism and the hoist rope spool, whereby the operation of the braking mechanism will move the hoist rope spool toward and from the crank shaft.

3. A well drilling machine, comprising a walking-beam, a crank shaft for connection with the walking-beam, a 80 spool for a hoisting rope, means for connecting the spool to the crank shaft, a spool for a drill rope, a connection between said spool and the crank shaft for operating said spool, a brake mechanism in connection with the spool, and a link connection between the brake mechanism and 85 the hoisting rope spool, whereby the operation of the braking mechanism will operate the means for connecting the hoisting rope spool with the crank shaft.

4. A well drilling machine, comprising a walking-beam, a crank shaft for connection with the walking beam, a friction wheel on the crank shaft, a spool for a hoisting rope, a friction disk on the spool, said spool being movable toward and from the crank shaft whereby to move the friction disk into and out of contact with the friction wheel, a spool for a drill rope, a connection between said 90 spool and the crank shaft for operating said spool, braking mechanism on the spool shaft, and means whereby the operation of the braking mechanism will move the hoist rope spool toward and from the crank shaft.

In testimony whereof I have signed my name to this 100 specification in the presence of two subscribing witnesses.

NELSON DOUGLAS WELLS.
